UNITED STATES PATENT OFFICE

WALTER E. SHIPP, OF WASHINGTON, DISTRICT OF COLUMBIA

DESIGN FOR AN ADVERTISING DEVICE OR SIMILAR ARTICLE

Application filed April 18, 1930. Serial No. 35,307. Term of patent 14 years.

To all whom it may concern:

Be it known that I, WALTER E. SHIPP, a citizen of the United States, residing at Washington, in the District of Columbia, have invented a new, original, and ornamental Design for an Advertising Device or Similar Article, of which the following is a specification, reference being had to the accompanying drawing, forming part thereof.

In the drawings:

The figure is a perspective view of the advertising device embodying my new design, the base portion being shown in dotted lines.

I claim:

The ornamental design for an advertising device or similar article as shown, and described.

WALTER E. SHIPP.
